(57) **CLAIM**

The ornamental design for a four wheels shopping cart as shown and described.

DESCRIPTION

FIG. 1 is a perspective view of a four wheels shopping cart showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 1;

FIG. 12 is a partial enlarged view of portion 12 in FIG. 1; and,

FIG. 13 is a partial enlarged view of portion 13 in FIG. 2.

The broken lines depict portions of the four wheels shopping cart and form no part of the claimed design.

The dot dash line is included for the purpose of illustrating the bounds of the enlarged view and forms no part of the claimed design.

1 Claim, 13 Drawing Sheets
